APPARATUS FOR CLEANING METALLIC ARTICLES

Rudolf Fritzsche and Arno Bauer, Berlin-Charlottenburg, Germany, assignors to Siemens & Halske, Aktiengesellschaft, Siemensstadt, near Berlin, Germany, a corporation of Germany

Application August 3, 1937, Serial No. 157,076
In Germany November 24, 1936

3 Claims. (Cl. 266--7)

Our invention relates to apparatus for cleaning metallic articles. In such apparatus the objects to be cleaned are placed in a perforated drum by means of which they are moved about in a cleaning bath. To this end, a suitable cleaning or pickling solution is employed in order to subsequently facilitate the electroplating of the metallic articles. It has been hitherto customary to move the containers with the articles to be cleaned in the cleaning solution either by hand or by means of a mechanical drive. However, such apparatus are, as a rule, expensive and unhandy in operation.

The object of our invention is to provide an economical cleaning apparatus of simple construction to operate. To this end, the apparatus consists of two inclined rollers spaced in parallel relation to each other. The rollers project preferably from above into the tank and are rotated in the same direction. The container designed in the form of a sifting drum rests on the two rollers and is thus caused to rotate by the roller drive. In this manner, the articles contained in the drum are flung about and are thus thoroughly cleaned by the solution contained therein.

In the accompanying drawing is shown an embodiment of the cleaning apparatus according to the invention.

30 Fig. 1 shows a sectional elevation.

Fig. 2 a top view of the novel cleaning apparatus, and,

Fig. 3 is a detail concerning a roller modification.

35 The two rollers *w*, each journalled in a bearing *a* at the upper end of the tank *b* and rotated in the same direction by means of an electric motor (not shown) are inclined at a given angle to the inner wall of the tank *b* containing the cleaning or pickling solution. The driving rollers are spaced in parallel relation to each other and may consist of wood or of any material of such nature as not to be corroded by the cleaning solution. Within the tank *b* is provided 40 a supporting arm *t* bent at its lower end to provide a bearing support both for the perforated drum *k* and for the driving rollers *w*. As will be seen from Fig. 2 the bent portion has two outwardly projecting arms *g* and an extension *e* provided with pivots in the form of thrust bearings *w'*, *w''* and *k'* respectively by means of which the free ends of the rollers and the bottom of the drum are supported. *h* designates the handle of the drum.

45 The surface of the rollers *w* may be provided

with protuberances *f* shown in Fig. 3 or be roughened in any suitable manner so as to facilitate the rotation of the drum *k*.

During the rotation of the drum the objects contained therein are continuously agitated and are thus cleaned thoroughly, all the more as the cleaning liquid continuously flows into and out of the interior of the drum through its perforations as well as through the upper opening thereof which lies partly below the liquid level.

5 The arrangement of the main bearings *a* for the rollers *w* outside the liquid permits a particularly good attendance of the bearings. In order to completely avoid the bearings *g* and *e* within the liquid the lower free ends of the rollers *w* may be supported only in the long bearing *a*, Fig. 1, and be provided with heavy end collars *u*, shown in Fig. 3, which support the lower edge of the drum *k*. To facilitate the cleaning of the liquid tank the bearings *a* may be so arranged as to be rotatable about a transverse pivot *d* so that the rollers may be entirely swung out of the tank.

20 We claim as our invention:

1. A cleaning apparatus for cleaning articles in a liquid, comprising a perforated cylindrical tumbling basket containing the articles, a tank containing the cleaning liquid, inclined rollers journalled adjacent to the tank edge and spaced substantially in parallel to one another and extending a suitable distance into the liquid, said basket being removably supported on the periphery of said rollers to be rotated in the liquid when both rollers are driven in the same direction, and means for supporting said basket at its lower end in the direction of its rotation axis.

2. A cleaning apparatus for cleaning articles in a liquid, comprising a perforated cylindrical tumbling basket containing the articles, a tank containing the cleaning liquid, rollers spaced substantially in parallel to one another, journals disposed at the edge of said tank for rotatably supporting said rollers, said journals being pivotally attached to the tank edge to permit the tilting of said rollers a suitable depth into the tank liquid in an inclined position, said basket being removably supported in the liquid in an inclined position on the periphery of said rollers to be rotated in the liquid when both rollers are driven in the same direction, and means for supporting said basket at its lower end in the direction of its rotation axis.

3. A cleaning apparatus for cleaning articles in a liquid, comprising a perforated cylindrical tumbling basket containing the articles, a tank

containing the cleaning liquid, inclined rollers and journals disposed adjacent to the tank edge for rotatably supporting said rollers, in an inclined position, said rollers being spaced substantially in parallel to one another and extending a suitable distance into the liquid, each of said rollers having a collar at its lower end for

removably supporting said basket in an inclined position on its periphery and at its end, to be rotated in the liquid when both rollers are driven in the same direction.
